UNITED STATES PATENT OFFICE.

PHILIP PALMGREN, OF YATES CENTER, KANSAS, ASSIGNOR TO J. C. CULVER, OF YATES CENTER, KANSAS.

AUTOMOBILE BRAKE-OPERATING MEANS.

Application filed October 27, 1924. Serial No. 746,180.

To all whom it may concern:

Be it known that I, PHILIP PALMGREN, a citizen of the United States, residing at Yates Center, in the county of Woodson and State of Kansas, have invented certain new and useful Improvements in Automobile Brake-Operating Means; and I do declare the following to be a full, clear, and exact description of the invention, such as will enable others skilled in the art to which it appertains to make and use the same.

A well known type of automobile in extensive use, is provided with a transverse brake-and-clutch-controlling rock shaft disposed under the front floor boards, said shaft having a pair of downwardly projecting arms which are connected with the front ends of brake rods extending to the hub brakes of the machine. The left-hand end of this shaft is provided with an upstanding hand lever by means of which it may be operated, and upon the enclosed types of machines, this lever stands directly in the door-way at the left-hand end of the driver's seat, making it very inconvenient to enter or leave the machine at the left side and often causing tearing of the clothing. It is the object of my invention to provide a simple and inexpensive construction which will enable operation of the above-named rock shaft, without equipping this shaft with the upstanding lever, this lever being entirely cut off from any machine which is equipped with my invention after manufacture, although it will be understood that the lever in question is merely omitted if the invention is installed at the factory.

Another object of the invention is to provide operating means for the above-named rock shaft, provided with a hand-grip disposed adjacent the instrument board of the machine, so that it may be quickly located and operated without the necessity of leaning forward to a great extent or looking downwardly into the cowl.

A still further object is to provide brake-operating means which may be easily connected with the left-hand downwardly projecting arm of the above-named rock shaft and the brake rod which is pivoted to said arm.

With the foregoing in view, the invention resides in the novel subject matter herein-

after described and claimed, the description being supplemented by the accompanying drawing.

Figure 1 is a side elevation partly broken away and in section, showing the application of my invention.

Figure 2 is a vertical transverse section taken substantially on line 2—2 of Fig. 1.

Figures 3 and 4 are perspective views showing different parts of the improved brake-operating mechanism.

In the drawing above briefly described, the numeral 1 designates the chassis frame of a well known form of automobile, 2 designates the cowl, 3 has reference to the instrument board, 4 designates the transverse frame-carried rock shaft which controls the clutch and the rear hub brakes, 5 has reference to one of a pair of downwardly projecting arms carried by said rock shaft, and 6 designates one of the brake rods which is provided with a fork 7 at its front end, straddling the lower end of the arm 5. The arm 5 is usually formed by an integral extension on the lower end of a hand lever which rises from the shaft 4 for the purpose of operating it. This lever, indicated at 8 in dotted lines, is cut off or omitted when using my invention, so that it will not obstruct the left-hand doorway, as now commonly occurs.

Spaced forwardly a considerable distance from the left-hand end of the rock shaft 4, is a vertically disposed lever 9 which is fulcrumed at 10 to a suitable bearing 11 secured by bolts or the like to the chassis frame 1. The lower end of the lever 9 is suitably connected with the lower end of the arm 5. Preferably, in establishing this connection, a link 12 is provided having adjustable forks 13 and 14 at its front and rear ends, the fork 13 being pivoted at 15 to the lever 9, while the fork 14 straddles the fork 7 of the rod 6, said forks 14 and 7 being both connected with the arm 5 by a single pin 16.

Pivoted at 17 to the upper end of the lever 9, I have shown a rearwardly projecting rod or bar 18 which passes slidably through a guide plate 19 secured to the instrument board 3, the rear extremity of said rod or bar being provided with a hand-grip 20. At the lower edge of the rod or bar 18, I have

shown a group of notches 21 forming teeth for engaging the guide plate 18 to hold the lever 9 in brake-applying position. I have also shown another notch 22 for engaging the plate to hold the lever 9 in proper position for retaining the shaft 4 in neutral position, for holding the clutch of the machine disengaged without applying the rear hub brakes. When the notch 22 is disengaged 10 from the plate 19, and the rod or bar 18 is forced forwardly to the limit permitted by a stop 23 thereon, the shaft 4 is in position to permit operation of the machine in the usual manner.

15 By providing the construction shown and described, or a substantial equivalent thereof, the doorway is not obstructed, and consequently, there is no danger of either tearing the clothing or releasing the shaft 4 and 20 throwing the machine into gear, when leaving or entering through said doorway. Moreover, the hand-grip 20 is more easily accessible than the usual hand lever 8, and it may readily be located without looking 25 downwardly into the cowl 2 and taking the eyes from the roadway. Thus, a number of accidents may be averted.

As excellent results are obtainable from the details disclosed, they may well be followed, but within the scope of the invention 30 as claimed, numerous minor changes may be made.

I claim:

1. In combination with an automobile having 35 a transverse brake-controlling shaft under the front floor boards, said shaft having a downwardly projecting arm; a vertically disposed lever spaced forwardly from the left-hand end of said shaft and disposed 40 sufficiently in advance of the driver's seat to prevent obstruction of the doorway at the left-hand end of said seat, fulcrum means for said lever mounted on the frame of the machine, means connecting the lower end of 45 said lever with the aforesaid arm, a hand-grip in rear of the upper end of said lever and operatively connected with the latter,

and means for holding the lever in different positions.

2. In combination with an automobile 50 having a transverse brake-controlling shaft under the front floor boards, said shaft having a downwardly projecting arm; a vertically disposed lever spaced forwardly from the left-hand end of said shaft and disposed 55 sufficiently in advance of the driver's seat to prevent obstruction of the doorway at the left-hand end of said seat, fulcrum means for said lever mounted on the frame of the machine, means connecting the lower end of 60 said lever with the aforesaid arm, a rod pivoted to the upper end of said lever and projecting rearwardly therefrom, said rod having a hand-grip on its rear end and being provided with longitudinally spaced teeth, 65 and a guide secured to the machine and slidably receiving said rod, said teeth being engageable with said guide to hold the lever in different positions.

3. In combination with an automobile 70 having a transverse brake-controlling shaft under the front floor boards, an arm projecting downwardly from said shaft, and a brake rod extending rearwardly from said 75 arm; a vertically disposed lever spaced forwardly from the left-hand end of said shaft and disposed sufficiently in advance of the driver's seat to prevent obstruction of the doorway at the left-hand end of said seat, fulcrum means for said lever mounted on the 80 frame of the machine, a link pivoted to and extending rearwardly from the lower end of said lever, the rear end of said link having a fork straddling the aforesaid arm and the front end of the brake rod, a single connecting pin passing through said fork, said arm and said brake rod, a hand-grip in rear of the upper end of said lever and operatively connected with the latter, and means for 85 holding the lever in different positions.

In testimony whereof I have hereunto affixed my signature.

PHILIP PALMGREN.
